UNITED STATES PATENT OFFICE.

ADOLPH PFEIFFER, OF CHICAGO, ILLINOIS.

DRAWERS.

Application filed October 8, 1924. Serial No. 742,280.

To all whom it may concern:

Be it known that I, ADOLPH PFEIFFER, a citizen of Russia, residing at Chicago, in the county of Cook and State of Illinois, 5 have invented certain new and useful Improvements in Drawers, of which the following is a specification.

This invention relates to underwear, with particular reference to the lower garments 10 or leg coverings, known generally as drawers.

One of the objects of the invention is to provide a pair of drawers with means for adjusting the waist-band to conform to the 15 person, in an easy and effectual manner.

Another purpose is to produce a pair of drawers in which the extremities or cuff 20 portions may be adjusted to fit with any desired closeness, and remain in such adjustment.

A further aim is in the provision of a pair of drawers, shaped in the usual manner and conformable at the points of contact 25 with the person to produce a comfortable fit which may be adjusted as desired.

These several aims and objects are attained by the novel construction and arrangement of parts hereinafter described and shown in the accompanying drawing, 30 forming part hereof, and in which:—

Figure 1 is a perspective view of an embodiment of the invention looking from the rear.

Figure 2 is an enlarged fragmentary view 35 of the upper rear portion of the same.

Figure 3 is a transverse sectional view, taken on line 3—3 of Figure 2.

Figure 4 is a transverse sectional view of 40 one of the legs at the lower end thereof.

Figure 5 is a fragmentary sectional view, taken on line 5—5 of Figure 4.

Referring more in detail to the drawing, the main portion of the drawers is designated by the numeral 10, and from this depend the legs 11, having flexible ends 12.

Sewn to the inner side of each leg terminal or cuff 12, are bands 13, forming a circuitous space 14 in which is contained a cord or tape 15, one end 16 of which is secured 45 permanently to the material of the drawer leg and thence passed through the space 14

to an opening 17 in the material, adjacent the secured end.

The extending portion 18 of the cord or band is formed with a loop 19 adapted to 55 engage a button 20 sewn on the leg over the band 13 not far from the opening 17.

Thus as the cord is drawn taut, the leg of the garment, at the cuff portion, will become contracted in diameter, to any de- 60 sired extent, causing the cuff portion 12 to fit in a neat and comfortable manner, as will be obvious.

At the upper end of the garment is a relatively broad waist band 21 sewn at its upper and lower edges, which may be fancifully shaped, this band and the garment being provided with the usual flies 22, carrying buttons or like fastening means at the front, and at the rear is a wedge-shaped 70 slit 23, separating the band into two substantially equal portions.

A cord or tape 24 is firmly secured to the band and garment on one side, as at 25, extended transversely across the slit 23 and 75 passed through the lower of two eyes formed in a plate 26 secured to the other side of the garment by stitches 27.

The cord is continued through the other plate eye and extended backward, parallel 80 with the lower portion, past the secured end 25, to be formed into several loops 28, any of which may engage a button 29 fixed on the band and garment material, in alignment with the upper strand of the cord, as shown. 85

Disposed over the cord or tape 24 is a partial cover 30, sewn at its edges, as best seen in Figures 1 and 3, forming a pocket through which the looped portion 28 of the cord extends. 90

In operation, the loops 28 are adjusted to engage the button 29 to give the desired degree of tightness to the band 21 and thus the garment is held comfortably to the person, upon buttoning the flies in the usual manner. 95

Having thus described my invention and set forth the manner of its construction and application, what I claim as new and desire to secure by Letters Patent, is:— 100

A pair of drawers having a sectional waist band and containing a wedge-shaped

slit at the rear, a cord permanently fixed to said band and garment on one side of the slit, a plate having two eyes spaced in vertical relation fixed on the opposite side of the garment, said cord extending in a level run through the lower eye and then through the upper eye to reach across the slit above and parallel with the first laid run and hav-

ing a plurality of loops at its free end, a button fixed on said garment to engage any 10 of the loops, and textile covering over said cord and eyes, through which the looped portion of the cord extends.

In witness whereof I have affixed my signature.

ADOLPH PFEIFFER.
